G. W. GOODRIDGE.

SHADE HOLDER.

APPLICATION FILED MAY 4, 1912.

1,032,821.

Patented July 16, 1912.

UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SHADE-HOLDER.

1,032,821.

Specification of Letters Patent. Patented July 16, 1912.

Application filed May 4, 1912. Serial No. 695,218.

To all whom it may concern:

Be it known that I, GILBERT W. GOODRIDGE, a citizen of the United States of America, and residing at Bridgeport, in the county of 5 Fairfield and State of Connecticut, have invented a certain new and useful Improvement in Shade-Holders, of which the following is a specification.

My invention relates to shade or globe 10 holders and particularly to the means by which such holder is attached to its support, for instance, to the lamp-receiving end of an electric lamp socket, the object of my invention being to provide an inconspicuous and 15 effective improved device for this purpose.

In the accompanying drawings, Figure 1 is a side elevation partially in vertical section, of a shade holder embodying my invention in one form and mounted on an electric 20 lamp socket; Fig. 2 is a plan of the shade holder body; Fig. 3 is a plan of the supporting ring; Fig. 4 is a perspective of the latter; Fig. 5 is a side elevation showing one manner of assembling the parts on the socket; 25 and Fig. 6 is a similar view of an alternative manner of assembly; Fig. 7 is an elevation of a portion of the shade holder body indicated by the line 7-7, Fig. 2.

The manner of supporting the globe or 30 shade upon the holder forms no part of the present invention. In the example illustrated, I have shown the common self-centering spring wire 10, the supporting guide loop 11, and recurved ends 12 and 13 of which 35 pass through slots in the peripheral skirt of the holder in well understood manner.

The holder is supported upon the customary bead 14 of the lamp shell 15 through an expandable ring 16. As here represented 40 this ring comprises a cylindrical collar portion 17, fitting the shell 15 above or below the bead in adjusted position as will be hereafter explained; a second section 18 inclined outwardly therefrom and overlying the supporting bead 14; and a coned section 19 connected to the section 18 by the narrow inwardly offset flange 20 and situated below or above the bead 14 depending upon the manner of adjustment, but in any event, opposite 45 to the position of the collar 17. This coned section 19 has spaced around the same a plurality of outwardly projecting ribs 21 projecting over and spaced slightly above the flange 20 to receive the flange 25 of the shade 50 holder body. Slots 22 are cut in the flange 20 to permit the metal to bend in slightly at the lower ends of the ribs 21 during adjustment. Spaced between the ribs 21 are inwardly-projecting, bead-engaging shoulders 23 at the base of the coned section 19. For 55 greater rigidity it is advisable to form one of these shoulders 23 adjacent each end of the split ring as shown.

The central aperture 24 of the shade holder body is bounded by a narrow flange 25, the 60 diameter of which is greater than that of the bead 14 so that the holder may be passed over the latter. A plurality of recesses 26 corresponding in number and location to the ribs 21 on the expanding ring are formed in the 65 flange, while in the arcs between them are formed pairs of bumps 27. An annular stiffening rib 28 may be formed around the flange 25 to add to the rigidity of the structure. 75

To assemble the parts, the ring 16 may be adjusted with the collar 17 lying either below (Fig. 5) or above (Fig. 6), the bead 14 on the socket shell. If it is to be adjusted below as in Fig. 5, the shade holder body 80 is first passed up over the bead 14, as shown. When the ring is in position the shade holder is pressed down, the ribs 21 passing through the recesses 26 in the flange 25, until the latter engages the flange 20. Rotation of the parts now with relation to each other passes the flange 25 beneath the lower edges of the ribs 21, thus preventing endwise separation of the parts, while continued rotation springs the lower end of each 85 rib 21 over one of the bumps 27, thus frictionally locking the parts together against further relative rotation. While the adjustment of the holder upon the ring prevents the latter from expanding and thus confines 90 it to the supporting bead 14, the frictional engagement between the ring and the bead is less than the frictional engagement between the holder and the supporting ring, so that the latter are rotated as a unit on 95 the bead after assembly.

Should the ring be adjusted as shown in Fig. 6, the holder is pressed upon the ring after the latter has been positioned. The engagement of the parts is the same, but the 100 shade holder is now supported not on the flange 20, but upon the edges of the ribs 21, and the ring engages the bead through the 105

collar 17 which is prevented from expanding by the adjustment of the holder on the ring.

I claim as my invention:—

- 5 1. A shade holder of the character described, having means for mounting the same upon a supporting bead, said means comprising an independent expansible ring reversibly adjustable upon said supporting bead, engaging elements on said ring and coöperating elements on the shade holder adapted to be brought into engaging relation with the related elements on the expansible ring from above or below the bead depending upon the manner of adjustment of said ring.
- 10 2. A shade holder of the character described, having means for mounting the same upon a supporting bead, said means comprising an independent expansible ring adjustable upon said supporting bead, a peripheral flange on said ring, a coned section rising from the flange and ribs thereon overlying said flange, in combination with a recessed flange on the shade holder body passed over said coned section and turned in adjusted position to engage between said peripheral flange and the overlying edge of said ribs.
- 15 3. A shade holder of the character described having means for mounting the same upon a supporting bead, said means comprising, as an element thereof, an independent expansible ring engaged by the body portion of the shade holder in assembled condition, said ring having a cylindrical portion, a portion overlying the supporting bead in adjusted position, and a

ribbed portion connected thereto by a perforated inwardly offset flange, substantially as described.

4. A shade holder of the character described having means for mounting the same upon a supporting bead, said means comprising an independent ring element 45 adapted to be positioned over the supporting bead, and a central flange on the shade-carrying body of the holder, adapted to be freely passed over the supporting bead, said flange being recessed on its inner periphery 50 and having engaging projections pressed up therefrom, to engage with coöperating elements on the independent ring element, substantially as described.

5. A shade holder of the character described having means for mounting the same upon a supporting bead, said means comprising an independent ring element adapted to be positioned over the supporting bead, and a central flange on the shade-carrying body of the holder, adapted to be freely passed over the supporting bead, said flange being recessed on its inner periphery 60 and having engaging projections pressed up therefrom, to engage with coöperating elements of the independent ring element, together with an annular stiffening rib surrounding said flange, substantially as described.

In testimony whereof I have signed my name to this specification, in the presence of two subscribing witnesses.

GILBERT W. GOODRIDGE.
